SHOE TAP PRESS

Louis J. Ripich, Cleveland, Ohio, assignor to The
Shoe Repair Specialty Corporation, Cleveland,
Ohio, a corporation of Ohio

Application July 20, 1935, Serial No. 32,359

3 Claims. (Cl. 12—33)

This invention has for its purpose a machine adapted for use in cementing leather toe taps on ladies' shoes.

Shoes worn by women according to present day styles and modes are of the pointed toe variety with very thin soles, and as a general rule the toe portion of the soles are the first to wear down. In the early days these worn toe portions of the sole were repaired by suitable leather patches nailed to the shoe last. This process did not provide a neat job of repairing. It was then discovered that these patches could be applied to better advantage and greater neatness, by the use of a cement or glue in place of nails.

15 In affixing these toe taps with cement or glue it was found necessary to apply a firm and even pressure on the taps while the cement or glue was in the process of drying.

One of the principal objects of my invention 20 is to provide a machine which under all conditions exerts a firm and even pressure on the shoe tap regardless of any irregularity encountered.

A further object is to apply heat to the tap for drying.

25 A further object of the invention is the easy access that the workman has in placing the shoes on the machine for the pressing action.

In the accompanying drawings:

Fig. 1 is a top plan view of a device for cementing taps upon the soles of shoes, the left shoe device being shown in open position and the right shoe device being shown in closed position.

Fig. 2 is a side elevation of Fig. 1.

Fig. 3 is a fragmentary elevation of the device, 30 showing a lug and spring attached to one side of the device.

Fig. 4 is an end elevation partly in section showing the relative positions of the working parts released and under tension.

40 Fig. 5 is an elevation similar to Fig. 3 with the shoe supporting member partly in section.

Fig. 6 is a top plan view of the shoe supporting member of the device, showing the heating element and method of wiring.

45 Referring to the drawings: The device comprises a base 16 which may be mounted upon a bench or other support; left and right shoe supporting members 11 and 12 are mounted upon said base and secured thereto by screws 13 through slots 14 and 15 in the oval base members 16 and 17 of the shoe supporting members 11 and 12.

The shoe supporting members or horns 11 and 12 are mounted substantially in parallel relation, the upper or shoe holding portions 18 and 19

being adapted to hold the left and right shoes of a pair.

An electrical unit 20 is mounted within a depression 21 in each shoe holding portion, the outlet plug 22 being mounted forward of the 5 oval base member 16, the wiring being substantially as shown in Fig. 6.

A pivot arm 23 is an integral part of the shoe supporting members 11 and 12, being relatively the same for each device and extending above 10 the center of the oval base member 17, this pivot arm 23 being of such shape as to form a stop 24 for the pivoting G shaped arm 25 when in operating position.

A spring 26 attached at one end by screw 27 15 to lug 28 on the pivot arm 23 holds the pivoting G shaped arm 25 in operative position by its pressure against the flat portion 29 of the pivoting G shaped arm 25.

A split lug 30 at the outer end of the pivoting 20 G shaped arm 25 supports a cam lever 31 on a pin 32 which motivates the working parts which comprise a floating pin or plunger 33 mounted within an aperture 34 in the split lug 30 and the pivoting G shaped arm 25 over which pin a spring 25 35 is superimposed, the upper end of said pin 33 being secured to a tongue 36 upon which the cam lever 31 exerts its pressure. A pin 37 is journaled through the lower end of pin 33 and is 30 slidably mounted within the slotted sides 38 and 39 of the top portion 43 of the pressure cup or head 41 which is carried thereby.

A compression spring 42 is inserted within the hollow orifice 43 in the top portion 40 directly 35 below the bottom surface of the floating pin 33 to ensure a uniform pressure upon the shoe tap regardless of any irregularity encountered.

In operation, the shoe 44 is placed in position over the shoe holding portion 19 of the shoe supporting member 12, the tap 45 being cemented to the sole of the shoe 44, the cam lever 31 is drawn upward by the operator, pivoting the G shaped arm 25 on the pivot pin 46 until the pressure cup 41 is just above the cemented tap 45, the cam 45 lever 31 is then pushed down to the position shown in the right hand device in Figs. 1, 2 and 4; the cam lever 31 pivoting upon the pin 32 presses against the tongue 36 compressing the spring 35 which seats within the split lug 30 above the 50 aperture 34 in the pivoting G shaped arm 25 and this forces the pin or plunger 33 down through the aperture 34 and compresses spring 42; due to the pin 37 being slidably mounted within the slots 38 and 39 in the top portion 40 of the pres- 55

sure cup 41, the spring 42 exerts a varied pressure on the pressure cup 41 which ensures a uniform pressure upon the tap being cemented. The current is then turned on and the unit 20 supplies the necessary heat to cement the tap securely to the shoe.

I claim:

1. A shoe tap press comprising a base having a projecting horn to fit within and support the toe of a shoe, a curved arm pivoted at one end to the base and arranged to swing its other end over the horn, a plunger slideable in the latter end of the arm, a head carried by the plunger, to apply pressure to a shoe tap on the horn, a spring between the plunger and head, and a cam carried by the arm and bearing against the plunger.

2. A shoe tap press comprising a shoe supporting member adapted to fit within the toe

of a shoe, a pivoted arm arranged to swing over said member, to press a toe tap against the shoe, a spring-supported plunger provided with a head for applying pressure to said tap, means carried by the arm to advance the plunger, and a spring between the plunger and the head, to cushion the latter. 5

3. A shoe tap press comprising a shoe supporting member adapted to fit within the toe of a shoe, a pivoted arm arranged to swing over said member, to press a toe tap against the shoe, a spring-supported plunger provided with a head for applying pressure to said tap, and means carried by the arm to advance the plunger, the means to advance the plunger including a cam 10 lever pivoted on the arm and bearing against the plunger. 15

LOUIS J. RIPICH.
